United States Patent Office

Des. 220,790
Patented May 18, 1971

220,790

IDENTIFICATION TAG BLANK

William T. Rives, 38 Decorie Drive,
Wilbraham, Mass. 01095

Filed June 16, 1969, Ser. No. 17,730

Term of patent 14 years

Int. Cl. D20—99

U.S. Cl. D96—3

FIG. 1 is a front perspective view of the identification tag blank showing my new design;

FIG. 2 is a rear elevational view thereof; and

FIG. 3 is a section view on an enlarged scale taken along line 3—3 of FIG. 2.

I claim:

A new and ornamental design for an identification tag blank, as shown.
